INVENTOR
BY *Victor J. Evans*

ATTORNEY

UNITED STATES PATENT OFFICE.

ERNEST G. FARSON, OF GREENCASTLE, MISSOURI.

INCUBATOR ALARM.

Application filed April 2, 1924. Serial No. 703,761.

The object of this invention is the provision of means for sounding an alarm when the temperature of a setting incubator reaches a higher or lower point than is desired.

5 The invention further consists in the construction, combination and operative association of parts such as is disclosed by the drawings which accompany and which form part of this application.

10 In the drawings:—

Figure 1 is a sectional view showing the improvement applied on the top of the incubator.

15 Figure 2 is a top plan view of the circuit maker.

Figure 3 is a perspective view of the spring.

Figure 4 is a similar view of the bracket to which the arm of the circuit maker is pivoted.

20 In the drawings the circuit maker is arranged on the top of the incubator. A dia-

phragm 21 within the incubating chamber 22 influences a rod 23 that is adjustably connected to a rod 24. The rod 24 is pivotally secured in a bracket 25 and has its outer end

25 loosely connected to the damper 26 of the heater 27 for the incubator chamber. On the top of the incubator chamber there is a sec-

ond forked bracket 28 between which there is received and to which there is pivoted an

30 arm 29. The arm is pivoted adjacent to one of its ends, the end of the arm nearest the pivot having arranged therethrough a screw

35 30 that contacts with the inner end of the rod 24. On the outer end of the arm 29 there is a forked circuit maker, the arms of which are indicated by the numerals 31 and 32 respectively.

Normally arranged centrally between the forked arms of the circuit maker there is a contact member 33. This member

40 is wired to a bell 34 in whose circuit there is an electric battery 35, the second wire of the circuit being connected to the circuit maker or to one of the bolts that attach the circuit maker to the arm 27.

45 Secured on the top of the incubator there is the straight end of an arched spring 36, the

said spring underlying the arm 29 and having a tendency to force the same upwardly to bring the arm 32 of the circuit maker against the contact 33 to complete the circuit and 50 sound the bell. This will occur when the temperature in the incubating chamber 22 reaches such degree that the rod 24 will be swung upwardly to raise the chamber 26. When the temperature in the incubating 55 chamber 22 is cooled the diaphragm 21 will contract, swinging the rod 24 in an opposite direction to impart a like swinging to the arm 27 to bring the element 31 of the circuit maker to engage the contact 33 and again sound the 60 alarm.

Having described the invention, I claim:—

A circuit closure of the temperature controlled type, comprising a casing having a chamber therein, a stationary contact mounted upon the casing and having a laterally extended upper end, a bracket on the casing, an arm pivoted intermediate its ends on the bracket and terminating at one end in a fork straddling the laterally extended end of the 65 stationary contact and adapted to engage therewith, a leaf spring mounted on the casing and engaging against the under side of said arm for normally holding it in neutral position with said fork out of engagement 70 with said stationary contact, a combined support and guide mounted on the casing, a lever pivoted intermediate its ends on said support and guide, an adjusting screw passing through one end of the arm and engaging said 75 lever, a depending member carried by said combined support and guide, said depending member being of tubular form, expansible wafers located within said chamber, and a rod connected with the wafers and slideable 80 through said depending member and connected with the lever near its pivot for moving the lever in accordance with temperature variations in the chamber.

85 In testimony whereof I affix my signature.

ERNEST G. FARSON.
